UNITED STATES PATENT OFFICE

CARL N. GUY, OF CANASTOTA, NEW YORK, ASSIGNOR TO BURDETT GUY AND COMPANY, OF CANASTOTA, NEW YORK

BURIAL VAULT

Application filed February 21, 1927. Serial No. 169,983.

This invention relates to a burial vault of the concrete metal lined type in which the marginal edges of the lid section are seated and supported upon an inner marginal ledge of the box lining leaving more or less clearance space between the marginal edges of the lid and outer walls of the ledge so that the lid may be easily placed in operative position upon the box ready for sealing when desired.

The main object is to provide a more convenient and efficient means for hermetically sealing the joint between the lid and box by first sealing the space between the marginal edges of the lid and outer walls of the ledge and then covering the sealed space and sealing means with additional cement of concrete cementitiously secured to the upper face of the box and to the adjacent edges of the lid thereby continuing the concrete casing of the box and lid across the joint between the box and lid and around the entire metal lining of both the box and the lid to render the burial casket air tight and water tight.

Other objects and uses will be brought out in the following description.

In the drawings:

Figure 1 is a perspective view of a burial vault embodying the features of my invention.

Figure 2 is an enlarged sectional view of a portion of the vault taken on line $x-x$, Figure 1.

As illustrated, this burial vault comprises a main body or box section —1— and a lid section —2— covering the open top of the box section.

The box section comprises an inner sheet metal box lining —3— and an outer casing —4— of concrete or analogous cementitious material preferably of considerably greater thickness than the metal lining —3— and reinforced throughout its area by open-mesh woven wire reinforcement —5— embedded in the concrete between the inner and outer surfaces thereof for increasing the tensile strength of concrete.

The sheet metal lining —3— of the box preferably comprises a bottom plate —6—, side plates —7— and end plates —8— se-

cured together at the corners by overlapping interlocking tinner's joints —9— which are preferably soldered together to form an air and water tight connection, it being understood that the lining —3— is co-extensive with the interior of the box —1— and watertight throughout its area.

The upper marginal edge of the lining —3— is offset outwardly and upwardly to form a marginal ledge —10— and a marginal flange —11— for supporting and retaining the lid —2— in operative position.

The concrete casing —4— is molded around and against the outer surfaces of the bottom, side and end walls of the lining —3— throughout their areas so as to form a substantially smooth exterior, said concrete casing being of nearly uniform thickness and its upper end is made to conform as closely as possible to the contour of the marginal ledge —10— and flange —11— and is, therefore, provided with a similar marginal ledge —10'— and flange —11'—, it being understood that the thickness of the concrete casing —4— is considerably greater than that of the lining —3— for strength and durability and for protecting said lining against contact with external objects and also against direct contact with external air and moisture.

The top faces of the sides and ends of the casing —4— and lining —3— are disposed in substantially the same horizontal plane for a purpose presently described.

The lid —2— is of greater area than the space within the marginal ledges —10— and —10'— but of slightly less area than the space within the marginal flanges —11— and —11'— to enable the lid to be easily placed in operative position upon the ledge thereby leaving a slight space between the marginal edges of the lid and flanges —11—.

As illustrated, this lid is arched upwardly transversely from its opposite side edges toward the center and also has its opposite ends inclined outwardly and downwardly as shown in Figure 1 to give strength to the lid and also to enable it to shed water, said lid comprising an inner sheet metal lining —12— and an outer casing section —13— of concrete similar to the casing section —4—.

of the box —1— except that its marginal edges terminate within the marginal flange —11—.

The marginal edges of the sheet metal lining —12— are provided with up-turned flanges —14— which assist in retaining the concrete section —13— in operative position against relative lateral or endwise movement and also forms a bearing adapted to rest upon the ledge —10—.

10 This concrete section —13— is also reinforced by a woven wire fabric —5— imbedded therein for reinforcing purposes.

When the marginal edges of the lid —2— are seated upon the ledges —10— of the box section —1— the up-turned flanges —14— terminate at about the same level as the top of the flanges —11— but in slightly spaced relation thereto as previously explained to enable the lid to be easily placed in operative position after which the intervening spaces or joints are filled with solder or equivalent material —15— to firmly bind the flanges —11— and —14— to each other and also to render such joint air tight and water tight 25 and at the same time assisting in holding the lid in operative position upon the ledge —10—.

The concrete section —13— is preferably 30 molded upon the outer faces of the inner lining —12— so that its marginal edges will lie in vertical planes substantially co-incident with the outer faces of adjacent portions of the flanges —14— thus forming with the upper faces of the sides and end of the box —1— a marginal recess —16— of rectangular cross section as shown in Figure 2.

After the filling seal —15— is properly inserted in the joint between the lid and box 40 the upper faces of the sides and ends of the concrete casing —4— and also the outer marginal edges of the concrete section —13— of the lid are roughened by acid treatment or otherwise whereupon an additional filler 45 —17— of concrete or cement is firmly tamped into the recess —16— to entirely fill the same throughout the marginal length and width of the box, the outer surface of the filler —17— being finished smoothly from the upper 50 outer edge of the lid section —13— to the upper outer edge of the concrete casing —4— so that the filler —17— will be substantially triangular in cross section and firmly knitted to the adjacent faces of the box and lid to 55 become a substantially unitary part of the casing —4— and section —13—.

It will be noted that the filler —17— extends entirely across the space between the flanges —11— and —14— and also across the 60 filler —15— thereby additionally sealing the joint and firmly holding the filler —11— in operative position to hermetically seal the lid upon the box.

Under this method of sealing the lid upon 65 the box it will be noted that the joint between

the lid and box is clearly exposed and enables the filling seal —15— to be conveniently and firmly incorporated in the joint at all points in the joint and that after this sealing operation is completed the recess —16— is also exposed and enables the operator to conveniently and positively fill in the concrete section —17— to complete the seal and at the same time to bind the lid upon the box.

What I claim is:

A burial vault comprising a concrete box-section having its top portion provided with an outwardly projecting marginal flange and an inner marginal groove in the horizontal plane of the flange, the bottom and outer wall 80 of the groove being disposed respectively in horizontal and vertical planes, a sheet metal lining covering the inner surfaces of the bottom, sides and ends of the concrete box section and having its upper marginal edge offset outwardly and upwardly to rest upon and against the bottom and outer upright walls of the groove, a concrete lid-section having its marginal edges overhanging the bottom of the groove within the outer upright wall 90 thereof, a sheet metal lining covering the inner surface of the concrete lid and having its marginal edge extended outwardly above the outwardly offset portion of the upper marginal edge of the box-lining and upwardly 95 within and in spaced relation to the upwardly offset portion of the upper marginal edge of said box-lining, a water proof filler in said space, and a concrete filler between the outer marginal edge of the concrete lid section and 100 upper surface of the marginal flange of the concrete box-section.

In witness whereof I have hereunto set my hand this 12th day of February, 1927.

CARL N. GUY.
